UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

SHELVES AND SUPPORTING MEANS THEREFOR.

1,110,342.

Specification of Letters Patent.

Patented Sept. 15, 1914.

Application filed May 14, 1913. Serial No. 767,682.

To all whom it may concern:

Be it known that I, GEORGE E. PICKUP, a citizen of the United States, residing at Newark, in the county of Licking and State 5 of Ohio, have invented certain new and useful Improvements in Shelves and Supporting Means Therefor, of which the following is a specification.

It is common to provide upon cook stoves, 10 and more especially upon the upper framework of steel ranges, a shelf or shelves adapted to support kitchen utensils, as for example a coffee pot.

My invention has reference to such 15 shelves and contemplates an improved swinging shelf construction in which the shelf is adapted to occupy a horizontal position when in use, and is further adapted to extend in a vertical position alongside 20 its supporting bracket or frame when not in use.

My invention further contemplates the 25 provision of improved means for supporting a pair of shelves upon a wall or frame member, one at the inner side and one at the outer side thereof, in such a manner that both may be freely swung from their vertical to their horizontal position, and vice versa.

30 One of the objects of the invention is to provide a shelf and supporting means in which the shelf when in its vertical position will lie within an opening in the supporting frame and substantially flush with 35 said frame.

Another object is to provide simple and 40 easily operated means for holding the shelf in its vertical position to prevent accidentally falling thereof. This means in the preferred form shown in the drawings acts to cause the shelf to automatically assume its vertical position when the shelf has been 45 swung upwardly to a certain point.

Other objects and advantages of the 45 invention will become apparent from the following detailed description.

In the accompanying drawings, Figure 1 50 is a perspective view of a side frame of a steel range having a pair of shelves mounted thereon by means embodying my invention, the shelves being shown in their open or horizontal position. Fig. 2 is a fragmental front elevation of a steel range illustrating 55 the relation of the frame and the shelves thereto. Fig. 3 is a fragmental vertical sec-

tional view through the rear portion of the shelves and the supporting means, the view showing the inner shelf in its horizontal position, and the outer shelf in its vertical position. Fig. 4 is a fragmental horizontal section in the plane of line 4—4 of Fig. 1 illustrating in plan view the shelves in their open position and the supporting brackets therefor.

Referring to Fig. 2 of the drawings, A 65 indicates the body of a steel range, B the top plate thereof, C the back, D the warming closet, and E a frame member extending upwardly from the top plate B and supporting one end of said warming closet. 70

In the preferred embodiment of my invention which I have illustrated in the drawings, the frame E is provided with an opening 5, and the two shelves 6 and 7, which will be herein termed the inner and 75 the outer shelves, respectively, are hinged to the frame E at the lower edge of the opening 5. Preferably, said opening is of the same shape as the shelves and has its edges beveled toward the outer face of the 80 frame E to complement similar bevel edges on the outer shelf 7, so that the latter shelf when in its vertical position will lie within the opening 5 and substantially flush with the frame E, the means for supporting said 85 shelf permitting the shelf to occupy this position. The frame E has a stop lug 8 projecting into the opening 5 and arranged to determine the proper position of the shelf 7. The inner shelf 6 may be slightly 90

larger than the opening 5, so that the edges of the shelf overlie the edges of said opening and form stop means to position the shelf. Said shelf may have a notch 9 to receive the stop lug 8, so as to permit the 95 shelf 7 to assume its proper position. When the two shelves are in their vertical positions, the inner faces thereof will lie in contact with or at least closely adjacent to each other. By this construction an extremely compact arrangement is provided, and by arranging the outer shelf 7 so as to lie flush with the face of the frame E, the appearance of the device is enhanced. Each of the shelves has a pair of trunnions 10 105 and 11, respectively, projecting horizontally from opposite lower corners of the shelves. Two pairs of small brackets 12 and 13 are secured to the inner and outer sides, respectively, of the frame member E adjacent 110

to the lower edge of the opening 5, each of said brackets having a vertical elongated recess 14 or 15 to receive one of the trunnions 10, 11. Preferably, the frame E has integral portions 16 offset toward its inner side, thus providing recesses 17 in the outer face of the frame in which the brackets 13 lie, and providing bosses 18 having recesses 19 in which the inner brackets 12 are seated. A bolt 20 extending through two adjacent brackets 12 and 13 and having a nut 21 threaded thereon, rigidly secures the brackets to the frame E. The recesses 17 and 19 assist in preventing a rotary movement of the brackets about the bolt 20.

As shown most clearly in Fig. 3, the trunnions 10 and 11 are offset outwardly, or in a direction away from the adjacent faces of the shelves when in vertical position, and the recesses 14 and 15 are correspondingly positioned with relation to the normal vertical positions of the shelves. Therefore, when the shelves occupy their vertical positions, the center of gravity will be at the inner side of or between the pivotal centers of the shelves, which are the centers of the trunnions 10, 11, so that gravity will act to hold the shelves in their vertical position. The shelves are further held in this position by the following means. The shelves have notches 22, 23 in opposite lower corners to permit the shelves to swing past the brackets 12 and 13. The upper or horizontal walls of these notches are beveled on their outer sides as indicated at 24 and 25, or in other words the said walls are provided with cams. In the upper end of the brackets 12, 13 are cam portions or notches 26, 27 which are arranged to coöperate with the cam portions 24, 25, so that when the shelves are in their vertical position, said cam portions will coöperate to resist outward or downward swinging movement of the shelves. When, however, force is applied to swing the shelves outwardly, the cam portions 24 and 25 will ride up on the portions 26 and 27 to permit such swinging movement. The horizontal position of the shelves is determined by stop portions 28 and 29 on the brackets 12 and 13 against which the shelves abut. When in this position, the trunnions 10 and 11 bear against the upper end walls of the recesses 14 and 15, as indicated by the shelf 6 in Fig. 3. Between the stop portions 28, 29 and the notches 26, 27, the brackets have arcuate or inclined surfaces 30, 31.

When the shelves are swung upwardly, the stop portions 28 and 29 act as fulcrums while the trunnions 10 and 11 are descending within the recesses 14 and 15. When the horizontal edges of the notches 24, 25 strike the arcuate surfaces 30, 31, the shelves ride up on said arcuate surfaces, carrying the trunnions upwardly in their recesses. As

soon as the cam portions 24 and 25 come into operative relation with the notches or cam portions 26 and 27, gravity acting upon the shelves will cause the shelves to drop into the recesses formed by the notches 26, 27, the coöoperating cam portions at the same time causing the shelves to swing inwardly into their normal vertical position. 70

While I have herein described my invention in considerable detail for the sake of clearness, I recognize the fact that various modifications may be made from the form shown in the drawings without departing from the spirit and scope of the invention, and I therefore do not limit myself to the form disclosed, except as defined by the scope of the appended claims. 75

I claim as my invention:

1. The combination of a support, a shelf mounted thereon for pivotal movement and arranged to occupy either a horizontal or a vertical position, a cam on said support sloping downwardly and toward said support, and a coöperating cam on the lower portion of said shelf arranged to be moved into coöperative relation to the first cam before the shelf reaches its vertical position, whereby the shelf will be automatically swung into such vertical position. 85

2. The combination of a supporting frame, a pair of brackets mounted thereon and having vertically elongated recesses, a shelf having trunnions extending into said recesses, a cam on the upper portion of one of said brackets, the face of said cam sloping downwardly and toward said supporting frame, and a cam on said shelf above its trunnion, said cams being arranged to be brought into coöperative relation before the shelf reaches its vertical position, whereby the shelf will be automatically swung by 90 said cams into such vertical position. 95

3. In a stove, the combination of a support having vertically elongated recesses, a shelf having a pair of trunnions extending into said recesses, said shelf being arranged to occupy either a horizontal or a vertical position, and coöoperating cam portions on said support and said shelf arranged to hold the shelf in its vertical position, said cam portions acting to raise the shelf when pulled outwardly whereby to disengage said cam portions and permit the shelf to swing down into horizontal position. 100

4. In a stove, the combination of a vertical supporting wall, a pair of brackets secured to one face thereof, a swinging shelf, trunnions and vertically elongated openings coöperating to pivotally connect said shelf to said brackets, said brackets having stop portions arranged to engage the shelf to support it in its horizontal position and having cam faces at their upper ends extending downwardly and toward said supporting wall, and coöperating cam portions 115 120 125 130

on said shelf, the engagement of said cam portions tending to swing said shelf into its vertical position.

5. In a stove, the combination of a vertical supporting wall having offset portions providing recesses on one face and bosses on its other face, a pair of brackets seated in said recesses, a second pair of brackets mounted on said bosses, means to secure said brackets to said wall, said wall having an opening therein, a pair of swinging shelves, means for pivotally connecting one of said shelves to one pair of said brackets to permit the shelf to lie in said opening flush with the wall when in its vertical position, and means pivotally connecting the other shelf to the other pair of brackets to permit the shelf to lie alongside said wall with its inner face adjacent to the face of the other bracket, said pivot means being so arranged that the line of direction of each shelf will fall between the axes of the pivot means, whereby the shelves will be held by gravity in their vertical position.

25 6. In a stove, the combination of a vertical supporting wall, said wall having offset por-

tions providing recesses on one face and bosses on its other face, a pair of brackets seated in said recesses, a second pair of brackets mounted on said bosses, trunnions 30 and vertically elongated openings coöperating to pivotally connect said shelves respectively to said brackets, said brackets having top portions arranged to engage said shelves to support them in horizontal positions and said brackets having cam faces at their upper ends extending downwardly and toward said supporting wall, and said shelves having coöperating cam portions, the engagement of said cam portions tending to swing said shelves into vertical position, said pivot means being so arranged that the line of direction of each of the shelves will fall between the axes of the pivot means, whereby the shelves will be 40 held by gravity in their vertical position.

In testimony whereof I affix my signature in the presence of two witnesses.

GEORGE E. PICKUP.
